UNITED STATES PATENT OFFICE.

JOSEPH B. STRAUSS, OF CHICAGO, ILLINOIS.

SUSPENSION LIFT-BRIDGE.

1,269,976.

Specification of Letters Patent. Patented June 18, 1918.

Application filed May 3, 1913. Serial No. 765,225.

To all whom it may concern:

Be it known that I, JOSEPH B. STRAUSS, a citizen of the United States, residing at Chicago, in the county of Cook and State of Illinois, have invented a certain new and useful Improvement in Suspension Lift-Bridges, of which the following is a specification.

This invention relates to suspension lift bridges and has for its object to provide a new and improved lift bridge of this description.

The invention is illustrated in the accompanying drawings wherein—

15 Figure 1 is a view showing one form of bridge embodying the invention;

Fig. 2 is a sectional view taken on line 2—2 of Fig. 1;

Fig. 3 is a sectional view taken on line 20 3—3 of Fig. 2;

Fig. 4 is a view showing a modified construction;

Fig. 5 is a view showing the operating and equalizing mechanism for the bridge span;

25 Fig. 6 is a view taken on line 6—6 of Fig. 1 with parts omitted;

Fig. 7 is a view showing a modified construction of connecting mechanism between the sections of the suspension device.

30 Fig. 8 is a view showing the section 6 separate from the supporting tower to show the connection of the brace to the tower.

Like numerals refer to like parts throughout the several figures.

35 Referring now to the accompanying drawings, I have illustrated a suspension bridge which has a main span suspended by a suspension device and adapted to be lifted vertically when it is desired to open the bridge.

40 In the construction shown in Fig. 1, there are two towers or supports 1 and 2. These towers or supports are mounted upon piers 3, and are preferably made up of members pivoted at their intersections as at 4 so that

45 the tower is free to move to compensate for variations in temperature, as hereinafter set out. The towers or supports are separated a suitable distance and there is a suspension device spanning the space between them, said suspension device consisting of a plurality of sections 5 and 6 movably connected with the towers 1 and 2, thus being an intermediate section 7, the intermediate section being movably connected with the other

50 portions of the suspension device. A mov-

able bridge span 8 is carried by the suspension device and is arranged to be moved vertically when it is desired to open the bridge. As shown in Fig. 1, the portions or sections 5 and 6 of the suspension device are 60 carried by the separated supports and are pivoted thereto at 9 so that they may be moved upwardly or downwardly. The outline shown by the dash lines at the upper ends of the towers 1 and 2 are ornamental 65 outlines indicating ornamental devices at the upper ends of the towers. Connected with each of the sections 5 and 6 is a counterweight 10, the counterweight being pivoted at 11 to the sections 5 and 6 and at 12 to a 70 connection 13. The connection 13 of the section 6 is pivotally connected to the supporting arm 14 (see Figs. 1 and 2) which is pivotally connected with section 6 and with the movable span 8. The connection 13 of section 5 is pivotally connected to a similar supporting arm 14 which is pivotally connected with section 5 and with the movable span 8. The intermediate movable portion 7 is connected by the supporting arms 15 75 with the movable span 8. The intermediate portion is also provided with a central connection 16 connecting it with the movable span 8.

In Fig. 2 I have illustrated a section showing the members 14 and 15 at one side of the bridge. There will be a similar set of members at the other side of the bridge. Connected with the end portion 6 are the hooks 17. These hooks are keyed to a non-rotating member 18 connected with the portion 6 and engage a pin or fixed device 19 on the intermediate portion 7 of the suspension device. As illustrated in Fig. 2, there are two hooks 17 at each side of the bridge. The portion 5 is provided with similar hooks 17. These hooks 17 connect the intermediate portion 7 of the suspension device with the portions 5 and 6 when the movable bridge span is closed so that a continuous suspension device is 100 provided upon which the movable bridge span is carried. Since these hooks 17 are connected to the fixed part 18, it will be seen that when the intermediate portion 7 is moved upwardly, the hooks will automatically 105 become disengaged from the parts 19, as shown for example in Fig. 4, and when the intermediate portion is moved downwardly, these hooks will automatically engage the parts 19. The intermediate por-

tion 7 is also connected with the ends of the movable bridge span 8 by means of the connecting pieces 20. The vertically movable bridge span 8 may be lifted by any suitable actuating mechanism. As herein shown, the span carries a motor 21 (see Figs. 1, 4 and 5) which is operatively connected with an equalizing shaft 22 extending along the span 8. This equalizing shaft is operatively connected with the cross shafts 23 near the ends of the span 8. These cross shafts are operatively connected with the pinions 24 which engage the toothed racks 25 associated with the towers or supports 1 and 2. It will thus be seen that the movable bridge span 8 will be moved upwardly when the motor is rotated in one direction and that because of the equalizing mechanism the two ends of the span will move equally so that the whole span will move vertically, and that this equal movement occurs both when the span is moved upwardly and downwardly.

In Fig. 7, I have shown a modified construction for connecting the movable intermediate portion 7 of the suspension device with the adjacent portions thereof. In this construction, instead of having the hooks 17, I provide slotted links 26 which are pivotally connected to the end portions 5 and 6 and which have slots 27 which engage the pins or fixed parts 28 on the movable intermediate section 7. When the sections of the suspension device are moved upwardly as shown in Fig. 4 the pins 28 slide along the slots 27 so as not to interfere with this movement. By this construction, the suspension device can be moved upwardly so that the portions 5 and 6 instead of being substantially horizontal as shown in Fig. 4, may be moved above the horizontal line connecting the pivots thereof to an angle equal to the angle below said horizontal line which they occupy when the bridge is closed. The towers or supports 1 and 2 are connected by rigid truss supports 29 to fixed supports 30, and the bridge approach spans 31 are suspended from these rigid truss supports. The towers or supports 1 and 2 having their members 50 pin-connected or pivoted together, and being pin-connected or pivoted to the piers, and being parallelograms, are free to move and change their shape when the rigid truss supports 29 lengthen and shorten under variations in temperature. In Fig. 4, the supports or towers 1 and 2 are mounted upon single piers 3 by means of a pivotal connection 32, this pivotal connection permitting relative movement thereof to compensate for variations in temperature. In Figs. 1 and 4 the connection between the members 29 and the towers are somewhat obscured by the overlapping members of sections 5 and 6. In Fig. 8 I have shown the upper end of the 65 tower and one of these sections separated in

order to show the connection of the member 29 to the tower. It will be noted that both the upper and lower chords of this member are connected to the tower.

When the bridge is in use, and it is desired to move the movable bridge span 8 upwardly, the motor 21 is set in operation so as to rotate the equalizing shaft 22. The movement of this shaft is transmitted to the pinions 24 so as to cause them to rotate. These pinions then travel along the racks 25 and cause the movable span to be lifted. The movement of the span then causes the suspension device to be moved, the interlocking or supporting connection between the intermediate portion 7 and the end portions 5 and 6 being rendered inoperative so as to permit relative movement between the intermediate portion and the end portions of said suspension device, the counterweight 10 counterbalancing the parts during this movement.

In Fig. 4, I have illustrated the bridge when the movable bridge span is lifted. When it is desired to lower the bridge span, the motor is reversed and the bridge span is lowered down to the position shown in Fig. 1, whereupon the intermediate portion 7 automatically interlocks with the end portions of the suspension device so as to form a continuous suspension member for supporting the bridge span 8, said suspension member carrying both the live and dead loads. The end sections 5 and 6 may be termed lifting arms, and they are arranged so that the outlines thereof harmonize with the bridge span so as to form a continuous appearing structure. Both the live and dead load stresses are transmitted through these lifting arms to the supports. It will be noted that in this construction the supports over the piers are so constructed that the sections 5 and 6, which are connected with the bridge span and carry the counterweight therefor, are connected to their respective supports beyond or outside of the pier center, there being provided means for counteracting the over-turning moment caused thereby so that the re-action comes upon the piers, these means in the particular construction shown being the rigid truss supports 29. 115

I claim:

1. A bridge comprising separated supports, a movable suspension device connected with said supports and spanning the space between them and varying in length when moved to open and close the bridge, a vertically movable bridge span connected with said suspension device, operating mechanism for varying the position of said suspension device so as to lift said bridge span, and means associated with the suspension device for compensating for the difference in length thereof when moved to its various positions.

2. A bridge comprising two supports on

- opposite sides of the space to be spanned by the bridge, a suspension device connected with said supports and spanning the space between them, a bridge span connected with 5 said suspension device, operating mechanism connected with said span so as to lift it, said suspension device provided with an intermediate section detachably attached to the remaining portion of the suspension device 10 and means for detaching said intermediate section from the remaining portion of the suspension device so that the bridge span may be moved upwardly.
3. A bridge comprising separated supports, a movable suspension device connected with said supports and spanning the space between them, a vertically movable bridge span connected with said suspension device, counterbalancing material connected with 20 said suspension device for counterbalancing the bridge span, and mechanism for moving the bridge span, and thereby operating the suspension device.
4. A bridge comprising separated supports, a movable suspension device connected with said supports, a vertically movable span connected with said suspension device, a counterbalance at each end of said suspension device for counterbalancing the 30 bridge span, and mechanism to lift said span, and thereby operating the suspension device.
5. A bridge comprising separated supports, a vertically movable bridge span between them, a rigid truss support connected with one of said supports, and an approach span suspended from said rigid truss support.
6. A bridge comprising separated supports, a single pier for each support, a pivotal connection between each support and its associate pier to permit expansion of the brace, an anchoring device connected with each support, a suspension device connected 45 with said supports and spanning the space between them, a vertically movable span connected with said suspension device so as to be supported thereby and means for moving the bridge span.
- 50 7. A bridge comprising separated supports, a movable suspension device connected with the supports and spanning the space between them, said suspension device provided with an intermediate portion mov- 55 ably connected with the other portions thereof, a vertically movable bridge span connected with said suspension device and operating mechanism to lift and lower said bridge span.
- 60 8. A bridge comprising separated supports, a suspension device connected with said supports and spanning the space between them, said suspension device comprising two end portions and an intermediate 65 portion movable with relation to said end portions, a vertically movable bridge span, the end portions and the intermediate portion of said suspension device being connected with said bridge span, and interlocking connections between the end portions 70 and the intermediate portion of said suspension device when the bridge span is in its closed position.
9. A bridge comprising separated supports, a suspension device connected with 75 said supports and spanning the space between them, said suspension device comprising two end portions, movably connected with the fixed supports and an intermediate portion movably connected with said end portions, a vertically movable bridge span, the end portions and the intermediate portion of said suspension device being connected with said bridge span, and interlocking connections between the end portions and the 80 intermediate portion of said suspension device when the bridge span is in its closed position.
10. A bridge comprising separated supports, a suspension device connected with 85 said supports and spanning the space between them, said suspension device comprising end portions movably connected with the supports and an intermediate movable portion connected with the end portions, a vertically movable bridge span associated with said suspension device, supporting arms connected with the bridge span and with said intermediate movable part, and supporting arms connected with said bridge span and the end portions of said suspension device, and interlocking connections between the end portions and the intermediate portion of said suspension device when the bridge span is in its closed position.
11. A bridge comprising separated supports, a suspension device connected with 90 said supports and spanning the space between them, said suspension device comprising end portions movably connected with the supports and an intermediate movable portion connected with the end portions, counterweights connected with said end portions for counterbalancing the span, a vertically movable bridge span associated with 95 said suspension device, supporting arms connected with the bridge span and with said intermediate movable part, supporting arms connected with said bridge span and the end portions of said suspension device and 100 connections between said latter supports and said counterweights, and interlocking connections between the end portions and the intermediate portion of said suspension device when the bridge span is in its closed position.
12. A bridge comprising two supports, two movable sections mounted thereon, a span connected therewith, a part connected with said span and engaging with the mova- 105 110 115 120 125 130

ble sections to form a continuous structure between the supports for carrying the loads coming on the span when closed.

13. A bridge comprising two supports, 5 two lifting sections mounted thereon, a bridge span connected therewith, an intermediate section connected with said span interposed between said lifting sections and connected with the movable sections to form 10 a continuous structure when the bridge is closed.

14. A bridge comprising separated supports, a suspension device connected with 15 said supports and spanning the space between them, said suspension device compris-

ing two end portions and an intermediate portion movable with relation to said end portions, a vertically movable bridge span, the end portions and the intermediate portion of said device being connected with said bridge span and locking connections between the ends of said intermediate portion and the ends of said end portions. 20

In testimony whereof, I affix my signature in the presence of two witnesses this 25 21st day of April, 1913.

JOSEPH B. STRAUSS.
